MUSICAL COMB OR SIMILAR ARTICLE

Taizo Ishida, 14 of 2, Tokiwa 4, Urawa-shi,
Saitamaken, Japan

Filed May 22, 1969, Ser. No. 17,286

Claims priority, application Japan Feb. 20, 1969

Term of patent 14 years

Int. Cl. D28—03

U.S. Cl. D86—8

FIG. 1

FIG. 1 is a top left front perspective view of a musical comb or similar article showing my new design; and

FIG. 2 is a left side view thereof, the pattern on the cylindrical handle portion being the same on the unseen side as that on the front.

I claim:

The ornamental design for a musical comb or similar article, as shown and described.
